(57) **CLAIM**

The ornamental design for a thread cutter and caddy combination, as shown and described.

DESCRIPTION

FIG. 1 is a perspective view of the thread cutter and caddy combination according to the present design;

FIG. 2 is a front view of the thread cutter and caddy combination as shown in FIG. 1, the rear view being a mirror image thereof;

FIG. 3 is a right side view of the thread cutter and caddy combination as shown in FIG. 1, the left side being a mirror image thereof;

FIG. 4 is top view of the thread cutter and caddy combination as shown in FIG. 1;

FIG. 5 is a bottom view of the thread cutter and caddy combination as shown in FIG. 1; and,

FIG. 6 is a perspective view with dashed lines showing environmental features of the thread cutter and caddy combination as shown in FIG. 1.

The broken lines depict environment that forms no part of the claimed design.
